UNITED STATES PATENT OFFICE

117,616

DESIGN FOR A TEXTILE FABRIC

Curt E. Forstmann, Montclair, N. J.

Application October 24, 1938, Serial No. 80,638

Term of patent 3½ years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design consists of parallel herringbone stripes embodying loose crooked stitches slightly obscuring the herringbone and imparting to the fabric the appearance of fine thread-like netting or tracery as shown.

I claim:

The ornamental design for a textile fabric, as shown and described.

CURT E. FORSTMANN,
